[57] CLAIM

The ornamental design for an airplane, as shown and described.

DESCRIPTION

FIG. 1 is a perspective view of an airplane showing our new design;

FIG. 2 is a top plan view thereof;

FIG. 3 is a side elevation view thereof, the opposite side being a mirror image of that shown;

FIG. 4 is a front elevational view thereof; and

FIG. 5 is a rear elevational view thereof.
